SAFETY MANICURING AND FINGER NAIL CUTTER COMBINATION

Melvin F. Hanson, Boston, Mass., assignor to
Morris Moshin, Boston, Mass.

Application December 30, 1933, Serial No. 704,664

4 Claims. (Cl. 30—23)

This invention relates to manicuring implements, and particularly to an implement combining in a single unit the functions of a cuticle cutter and a nail cutter.

Objects of the invention are to provide a combination implement for performing the above functions which will be extremely simple in construction and unusually efficient in operation; which will be capable of commercial manufacture at low cost; which will cut with equal facility either the cuticle or the nails; which when used as a cuticle cutter will trim the cuticle without danger of cutting too deeply into the cuticle; and finally which will provide the maximum leverage with the minimum of weight and size so as to enable it conveniently to be carried in the pocket or the purse.

These objects, together with certain other structural and operational advantages which will appear more fully hereinafter, are attained in the device of the present invention.

In the accompanying drawings, I show one structural embodiment of my invention which I have found highly satisfactory in actual service and well adapted to the requirements of commercial manufacture.

Such embodiment may be taken as typical of the principles involved, although it will be understood that it is selected as illustrative only and that my invention is capable of various modifications in structure and design.

Figs. 1, 2 and 3 are top, side, and bottom views, respectively, of a manicure implement in accordance with my invention.

Fig. 4 is an enlarged section on the line 4—4 of Fig. 1.

Figs. 5, 6 and 7 are sections on the lines 5—5, 6—6 and 7—7, respectively of Fig. 4, and

Figs. 8 to 13 inclusive are detailed views of individual parts, removed.

My combination implement is of the pliers type. It includes a pair of crossed handles 20 and 21 of steel, aluminum, or the like. These are pivoted together as at 22 and are normally held open by a spring 23 interposed therebetween.

Any suitable means may be employed for locking the handles closed when the implement is not in use. As here shown, a latch 24 is pivoted at 25 to the extremity of one handle. The loop end 26 of said latch is adapted to lock within a slot 27 at the extremity of the other handle. Obviously, of course, other forms of locking device may be used, or the locking device may be entirely omitted if desired.

If desired, a nail file and cleaner 28 may be

pivoted, as at 29, to the under face of one of the handles. When not in use, the file 28 may be locked in an out-of-the-way position against the under face of the handle to which it is pivoted. This may be conveniently accomplished by forming the under face of the handle with a pair of spaced locking lugs 30 between which the pointed end of the file 28 is adapted to be frictionally lodged.

Beyond the pivot 22 the handles extend as opposing jaws 20a and 21a. The inner faces of these jaws are oppositely recessed from side to side, as indicated at 20b and 21b to provide sockets within which a pair of coacting nail cutters 31 and 32 are removably mounted.

Each cutter presents right and left hand cutting blades 31a and 31b, and 32a and 32b, respectively, the opposing edges of which are sharpened for coaction with each other when the jaws are closed towards each other.

Preferably the respective cutter blades of each cutter are oppositely curved as at 31c and 32c to correspond substantially to the normal curvature of the finger nails of the right and left hands.

Preferably, also, the lateral faces of the jaws beyond the recesses thereof are laterally cut away as indicated at 20c and 21c to permit the nail to be conveniently inserted between one or the other of the pairs of the opposing cutter blades, accordingly as to whether the implement is being used to cut the nails of the right or left hand.

The cutters themselves may be of any desired construction. Preferably they are detachable so that they may be removed from their mounting sockets and sharpened or replaced by new cutter units when dulled.

Preferably also each cutter is constructed as a unit (see Figs. 10 and 13) in the form of a die or block presenting a base 31d or 32d bottoming on the mounting sockets. From said bases rise the blades 31a, 31b or 32a and 32b.

These cutter units may be detachably but securely retained in their mounting sockets in any desired manner. Their frictional fit within the sockets may be sufficiently tight to accomplish this, or the units may be positively fastened, as by means of attaching screws 33 or the like set flush within the jaws.

Beyond the cutters, the jaws extend as supporting surfaces 20d and 21d for a pair of opposing cuticle cutters 34 and 35 which are preferably detachably mounted thereon.

The cutter 34 is a flat blade mounted on the inner surface of the jaw extremity 21d in any suitable manner and extending axially therebe-

110

yond. Preferably, the inner end of the blade 34 is longitudinally slotted as indicated at 34a to slide over a pair of headed positioning studs 36 and 37 fixed to the inner face of said jaw extremity. (See Fig. 4.)

Beyond said jaw extremity, the blade 34 extends as a combination guard and cutter. The lateral edges of such cutter are curved inwardly towards each other and sharpened as indicated at 34b and 34c, being separated from each other by a re-entrant slot 34d disposed substantially centrally of the outer end of the blade. (See Fig. 9.)

Thus the outer end of the blade 34 presents a pair of oppositely curved cutting surfaces 34b and 34c. These constitute right and left hand cutting edges adapted for coaction with the similarly curved cutting surfaces of the opposite cuticle cutter 35.

The cutter 35 is formed as a pair of blade elements 35a and 35b. (See Figs. 11 and 12.) These extend back into the jaw extremity 20d, said extremity being slotted as at 20e to receive the blades and the blades being detachably mounted in said slots in any suitable manner, as by indenting the rear ends of the blades as at 38 and by forming the jaw extremity with opposite recesses 39 within which said indented portions are detachably received.

Beyond the jaw extremity 20d the blades 35a and 35b are curved inwardly towards each other on arcs of slightly larger radius than the curvature of the cutting blades 34b and 34c of the coacting cutter 34.

When the jaws are pressed towards each other, the blades 35a and 35b travel past the blades 34b and 34c, outwardly thereof, to effect a shearing cut, the adjacent edges of the blades 35a and 35b being sharpened as at 35c and 35d to coact with the sharpened lateral edges of the blades 34b and 34c.

In assembling the implement, the handles are pivoted together with the nail cutters 31 and 32 mounted in their receiving sockets, and the cuticle cutters 34 and 35 mounted on the jaw extremities in the relation described.

In operating the implement as a nail cutter, the opposing cutting blades 31a and 32a at the left side of the implement would naturally be used to cut the left hand nails if the implement were held in the right hand, and the opposing blades 31b and 32b at the right side of the implement would naturally be used to cut the right hand nails if the implement were held in the left hand.

In operating the implement as a cuticle cutter, one side edge of the flat cutter blade 34 is inserted under the cuticle. When the jaws are pressed together, the sharpened edges 35c and 35d of the cutter blades 35a and 35b travel past the beveled side edges 34b and 34c to produce shearing cuts.

If the instrument be held in the right hand to cut the cuticle of the left hand, the cooperating cutting edges 34b and 35c effectively coact as a shear. If the instrument is held in the left hand, the cooperating cutting edges 34c and 35d effectively coact as a shear.

Regardless of whether the cuticle of the right or the left hand is being cut, the blade 34 acts as a guard to prevent the cuticle from being too deeply cut.

Moreover, the wiping or shearing action of the cutting edges 34b and 35c and 34c and 35d past each other tends to make these blades self-sharpening to some extent in action.

On account of the construction and manner of

mounting the nail and cuticle cutter blades, it is possible to cut nails and/or cuticle on any desired radius.

Inasmuch as the several cutter units are all detachable and replaceable, it is within the purview of my invention to furnish with each implement one or more extra sets of cutters as replacements.

Although I have described my manicure implement as a combination nail and cuticle cutter it may obviously be used for other purposes, as in certain surgical uses, or for cutting corns, callouses etc.

Similarly, I recognize that many variations in structural and functional details are possible. All such are to be regarded as included within the spirit and scope of my invention, if within the limits of the appended claims.

What I therefore claim and desire to secure by Letters Patent is:—

1. A manicuring implement, comprising a pair of crossed pivoted handles providing spaced jaws terminating in mounting portions, a pair of opposing cuticle cutters mounted on said jaw terminals, one of said cuticle cutters consisting of a relatively flat single blade, having its lateral edges curved towards each other and sharpened to provide a pair of cutting edges, the coacting cuticle cutter comprising a pair of spaced blades the rear ends of which extend along either side of the longitudinal axis of the jaw terminal on which said blade pair is mounted, the forward ends of said pair of blades being curved towards each other and having their edges opposite the single blade sharpened, and the arcs of curvature on which the pair of blades were developed being greater than those on which the lateral cutting edges of the single blade were developed so that the sharpened edges of the pair of blades pass outside of the sharpened lateral edges of the single blade and produce a shearing cut between said coacting cutting edges.

2. A manicuring implement as claimed in claim 1 wherein the jaw terminal on which the pair of blades is mounted is longitudinally slotted at either side of its central median line to receive the rear ends of said pair of blades and is also provided with a pair of locking recesses and wherein the rear ends of said blades are formed with indentations adapted to enter and be frictionally retained within said locking recesses.

3. A manicuring implement, comprising a pair of crossed pivoted handles providing spaced jaws terminating in mounting portions, a pair of opposing cuticle cutters mounted on said jaw terminals, one of said cuticle cutters consisting of a relatively flat single blade, the rear end of which overlaps the inner face of its jaw terminal and has a longitudinal slot; a headed fastening extending through said jaw terminal with its head disposed in said slot for adjustably and detachably fastening said blade to said terminal, said blade beyond said terminal having its lateral edges curved towards each other and sharpened to provide a pair of cutting edges, and having at its forward end an axial slot separating said rounded cutting edges, the coacting cuticle cutter comprising a pair of spaced blades the rear ends of which extend rearwardly of the opposite jaw terminal at either side of the longitudinal axis thereof, said pair of blades beyond said terminal being curved towards each other and having their edges opposite the single blade sharpened, and the arcs of curvature on which the pair of blades were developed being greater than those on which the lateral cutting edges of the single blade were developed so that the sharpened edges of the pair of blades pass outside of the sharpened lateral edges of the single blade and produce a shearing cut between said coacting cutting edges.

blade were developed so that the sharpened edges of the pair of blades pass outside of the sharpened lateral edges of the single blade and produce a shearing cut between said coacting cutting edges.
5 4. A manicuring implement as claimed in claim 3 wherein the jaw terminal on which the pair of blades is mounted is longitudinally slotted

at either side of its central median line to receive the rear ends of said pair of blades and is also provided with a pair of locking recesses and wherein the rear ends of said blades are formed with indentations adapted to enter and be frictionally retained within said locking recesses. 80
